UNITED STATES PATENT OFFICE.

ANTON S. ANDERSON, OF CHICAGO, ILLINOIS.

WINDOW-CLEANING DEVICE.

No. 907,553.

Specification of Letters Patent.

Patented Dec. 22, 1908.

Application filed May 9, 1908. Serial No. 431,828.

To all whom it may concern:

Be it known that I, ANTON S. ANDERSON, a citizen of the United States, residing at Chicago, county of Cook, and State of Illinois, have invented certain new and useful Improvements in Window-Cleaning Devices, of which the following is a specification.

My invention relates to window cleaning devices, and particularly to a window cleaning device for cleaning the outer surface of the windows by a person within the room.

The object of my invention is to provide a device of the class mentioned, which shall be of simple construction and readily operated.

Other objects will appear hereinafter.

With these objects in view, my invention consists generally in a base portion adapted to rest upon a window sill, a standard secured in vertical position to each end of said base, a cleaning device slidably mounted on one of said standards and means arranged on the other standard for operating said cleaner.

My invention further consists in a base portion, a standard secured to each end of said base and rising vertically therefrom, a cleaning device slidably mounted on one of said standards, a rotary member on the other standard, a cord operatively connecting said cleaner and said rotary member, and means for automatically taking up the slack in said cord.

My invention further consists in various details of construction and arrangements of parts, all as will be hereinafter fully described and particularly pointed out in the claims.

My invention will be more readily understood by reference to the accompanying drawings, forming a part of this specification, and in which—

Figure 1 is a side elevation of a window cleaning device embodying my invention in its preferred form, a portion of the window sill and the sash being shown in section, Fig. 2 is a bottom plan view of the device, Fig. 3 is a vertical section of the device on the line $x-x$ of Fig. 1, Fig. 4 is a rear face view of the cleaner block or rubber, and Fig. 5 is a detail section of the sliding cleaner upon an enlarged scale, the section being taken on the line $y-y$ of Fig. 1.

Referring now to the drawings, 1 indicates the base portion of the device, which is preferably quite thin, and which may be made of any suitable material such as wood or metal. When the device is in operative position, the base portion rests upon the window sill and

projects beneath the sash which is lowered upon the same. It is to the end that the sash may be lowered as far as possible that the base 1 is made as thin as is practical. Both the outer and inner ends of the base portion are considerably thickened, forming the raised portions 2 and 3 respectively, in which are secured the standards 4 and 5 extending vertically upwards therefrom. The cleaning device proper is slidably mounted on the outer standard 4, and is moved up and down thereon to clean the window. To this end, the standard 4 is made of sufficient height to reach to the top of the sash. The inner or inside standard is of less height and carries the mechanism for reciprocating the cleaner.

The cleaning device proper comprises a sleeve portion slidably mounted on a standard, an arm extending therefrom, and a cleaner block detachably and pivotally connected to the end of the arm and equipped with means for attaching a cloth or other cleaning device thereto.

6 indicates the sleeve, and 7 the arm extending horizontally therefrom. The end of the arm 7 is provided with a horizontally disposed cylindrical member 8 formed integrally therewith, and constituting means for attaching the cleaner block.

9 indicates the cleaner block, which is preferably rectangular, and provided upon its rear face with a split sleeve 10, which slips longitudinally upon the member 8. If preferred, a slight play of the block may be permitted, the joint 8—10 acting as a pivot joint, or the joint may be rigid if preferred.

11 indicates a pin extending through the sleeve 10 and an aperture 12 in the member 8 to prevent accidental separation of the parts while in use, and the sleeve is slotted to receive the pin and permit play of the block.

In using the device, the front face 13 of the block 9 is covered with a cloth, and to this end, the block is equipped with means for securing the cloth thereto. This comprises a pair of metal strips 14 and 15 having upturned flanges 16 and 17 respectively, to which are secured a plurality of pins 18, 105 those on the flanges 17 being adjacent to or extending slightly beyond the lower edge of the block. The cloth is first secured to the pins on the flange 16 turned about the front face of the block and then secured to the pins 18. It is obvious that the cloth is easily removed for rinsing and replaced.

19 indicates a roller arranged in the sleeve 6 at the base of the arm 7 to prevent friction between the sleeve and the standard when the device is pressed against the window pane. Arranged upon the standard 5 is a band wheel 20 having a handle 21 by means of which it is rotated. The band wheel 20 is connected by a cable 22 to the sleeve 6 in such a manner that by rotating the wheel, in one direction, the sleeve will be raised, and by turning it in the opposite direction, the sleeve will be lowered. To this end, the cable or cord 22 passes down, and about the rollers or pulleys 23—24 arranged within the base upon each side of the standard 5, thence about similar rollers 25 and 26 in the base 1 upon each side of the standard 4. The cord then passes upwardly and about a roller 27 arranged in a recess 28 at the upper end of the standard 4. To permit the cord or cable to pass freely between the sill and sash, the base 1 is longitudinally grooved as at 29 to receive the horizontal portions of the cable between the rollers 23 and 24, and 25 and 26. The standards 4 and 5 are arranged substantially on the central axis of the base which brings the band wheel 20 to one side of its respective standard, whereas the roller 27 is substantially central of the standard 4, hence the groove 29 is arranged at an angle as shown clearly in Fig. 2.

Suitable means are provided for taking up the slack of the cable 22. This comprises a pair of arms 30 and 31 pivotally mounted upon the stud shaft 32 upon which the wheel 20 is mounted. These are provided at their lower ends with rollers 33—33, which rest against the outer edges of the cable.

34—34 indicate springs which draw the rollers 33 tight against the cable, taking up the slack. These may either be attached to the standard 5 or to each other. As shown

in the drawings they are attached to a pin fixed to the standard 5. The standard 5 extends above the wheel 20 a sufficient distance 45 to form a grip 35, by means of which the device may be held in position with one hand while the wheel is turned with the other. Upon the upper end of the standard 4 is arranged a cushion 36 preferably a rubber cap 50 or ball to prevent the end of the standard from breaking the window should it accidentally be forced against it.

Having described my invention what I claim as new, and desire to secure by Letters Patent, is:

1. In a device of the class described, a base in combination with a standard extending upwardly from the end thereof, a sleeve slidably mounted on said standard, a horizontal arm extending from said sleeve and having a horizontally disposed cylindrical member formed upon the end thereof, and a cleaner block having a split sleeve to engage said cylindrical member, substantially as described. 60

2. In a device of the class described a base block, in combination with a standard extending vertically upwards from each end thereof, a cleaner slidably mounted upon one of said standards, a band wheel mounted upon the other standard, a cable connecting said cleaner and said wheel, a pair of arms pivotally mounted adjacent to said wheel and means for causing said arms to exert yielding pressure upon said cable, substantially as described. 70

In testimony whereof I have signed my name to this specification in the presence of two subscribing witnesses.

ANTON S. ANDERSON.
